OSKÁR KLEIN, OF NEW YORK, N. Y., ASSIGNOR TO JACOB TRUCHINSKY, OF NEW YORK, N. Y.

PERMUTATION-LOCK.

1,241,636.

Specification of Letters Patent.

Patented Oct. 2, 1917.

Application filed December 22, 1916. Serial No. 138,392.

To all whom it may concern:

Be it known that I, OSKÁR KLEIN, a subject of the King of Hungary, and a resident of the city of New York, borough of Manhattan, in the county and State of New York, have invented a new and Improved Permutation-Lock, of which the following is a full, clear, and exact description.

This invention relates to locks of the permutation type and has for its general objects to improve and simplify the construction and operation of devices of this character so as to be reliable and efficient in use, comparatively simple and inexpensive to manufacture, and so designed that the combination can be easily and quickly changed whenever occasion requires.

A more specific object of the invention is the provision of a lock of that type including a barrel rotatably mounted in a stationary casing, there being novel means within the barrel for operatively connecting the barrel with the latch or bolt, whereby the latter is thrown outwardly or withdrawn by the cam action between the bolt and the edges of the bolt opening in the barrel as the latter is rotated.

A further object of the invention is the provision of a novel arrangement of tumblers and baffle plate with means whereby the barrel of the lock can be operated so as to act as a bolt-throwing means by the pressing of a button when the tumblers are in the desired position.

With such objects in view, and others which will appear as the description proceeds, the invention comprises various novel features of construction and arrangement of parts which will be set forth with particularity in the following description and claims appended hereto.

In the accompanying drawings, which illustrate one embodiment of the invention and wherein similar characters of reference indicate corresponding parts in all the views,

Figure 1 is a front view of the lock applied to a door and the bolt being shown in locking position by dotted lines;

Fig. 2 is a vertical section of the lock on the line 2—2, Fig. 3;

Fig. 3 is an enlarged horizontal section on the line 3—3, Fig. 2;

Fig. 4 is a vertical section on the line 4—4, Fig. 3, drawn on a reduced scale;

Fig. 5 is a section corresponding to Fig. 3 with the push button pressed in preparatory to the throwing of the bolt;

Fig. 6 is a sectional view on the line 6—6, Fig. 3, showing the relation of the tumblers 60 to the baffle plate;

Figs. 7 and 8 are sectional views, respectively, on the line 7—7 and 8—8, Fig. 3, drawn on a reduced scale;

Fig. 9 is a sectional view on the line 9—9, Fig. 5, drawn on a reduced scale;

Fig. 10 is a perspective view of one of the tumblers;

Fig. 11 is a perspective view of the locking post for preventing the baffle plate from turning except when the tumblers are in the required position for locking and unlocking the bolt;

Fig. 12 is a detail sectional view on the line 12—12, Fig. 3; and

Fig. 13 is a detail sectional view on the line 13—13, Fig. 3.

Referring to the drawing, 1 designates a door or equivalent body, and 2 the door jamb, which latter has a latch plate 3 into which the latch or bolt 4 is adapted to engage to lock the door 1 in closed position. The permutation lock A is mounted in a socket 5 in the door and the bolt is thrown into and out of locking position through a slot 6 in the door.

The lock A comprises a stationary casing 7 suitably fastened in the door, and within the casing is rotatably mounted the barrel 8, which has one end projecting out from the outer face of the door so as to form a rim which can be gripped for turning the rotatable part of the lock, said projecting part being circular and bearing an alphabetical index 9, whereby the desired permutations can be obtained. The front end of the barrel has a circular opening 10 from which project the tumblers 11, whereby the latter can be manipulated, and also projecting out of the open end of the barrel is a pushbutton 12 for enabling the barrel to be operatively connected with the bolt for throwing or withdrawing the same. The open or face end of the barrel is closed by a disk or face plate 13 which is provided with posts 14 that are fastened by screws 15 to an inner plate 16, the latter in turn being fastened by screws 17 to an internal flange 18 on the barrel. By this means the face plate 13 is supported in the barrel with

75

95

100

105

110

an annular space 19 between the periphery of the plate 13 and the internal surface of the barrel, such annular space serving to accommodate the tumblers 11. The tumblers, of which there are four in the present instance, have external lugs 20 which are engageable by the fingers to adjust the tumblers to the desired position, and the inner ends of the tumblers have laterally extending lugs 21 which coöperate with a baffle plate or disk 22 to control the operation of the lock. The tumblers are free to be moved laterally in the annular space 19 when the baffle plate 13 is in its normal position. The outer extremities 20 form knobs or grips whereby the tumblers can be engaged by the fingers for moving them. Each tumbler has within its body a spring-pressed follower 23 which, by engaging in any one of a series of recesses 24 on the inner surface of the index-carrying flange 9, insures the holding of the tumblers in position to which they are adjusted. The inner ends of the tumblers engage an annular internal shoulder 25 on the barrel. The baffle disk 22 is provided in its periphery with a series of recesses 26, and all of these recesses, except four, are closed by adjustable baffling devices in the form of screws 27, four slots being left vacant so as to coöperate with the four tumblers to enable the desired combination for operating the lock to be obtained. This baffle disk will preferably have the recesses lettered to correspond with the alphabetical index 9 on the front of the barrel. When the tumblers are adjusted so that they register with their respective open slots 26 in the baffle disk, the latter can be shifted from the position shown in Fig. 3 to that shown in Fig. 5, which is the position the baffle disk occupies when the bolt is being thrown to and from locking position by the turning of the barrel 8. This shifting of the baffle plate is performed by the pushbutton 12, which engages the baffle plate or disk 22 at the point 29. Behind the baffle plate are helical compression springs 30, which yieldingly hold the baffle plate forwardly against the face plate, as shown in Fig. 3. The springs 30 are kept in place by the retaining plate 16.

The bolt 4 has its end 31 pivoted at 32 to a suitably fixed part, such as the inner arm 34 of a bracket 35, which is fastened as shown in Fig. 4 to the fixed casing 7 of the lock. The bolt passes through a slot 36, the edges 37 and 38 of which, as the barrel turns, have a cam action on the bolt to respectively project or withdraw the latter, as will be clearly apparent by reference to Figs. 2 and 9. When the barrel is turned in an anti-clockwise direction, Fig. 9, the edge 37 of the slot in the barrel will project the bolt to the position shown in Fig. 2, and when the barrel is turned in the oppo-

sition direction the bolt is withdrawn. The barrel is turned through one hundred and eighty degrees to project or withdraw the bolt and the casing of the lock has a slot 39 slightly greater than one hundred and eighty degrees to accommodate the motion of the bolt. The bracket 35 has fastened to its arm 34 a forwardly projecting central shaft 40 which is stationary and carries at its forward end oppositely extending lugs 41 which engage in a diametrical recess 42 in the baffle plate 22, whereby normally the latter is prevented from turning, but when the pushbutton is pressed inwardly from the position shown in Fig. 3 to that shown in Fig. 5, the lugs 41 do not lie within the recess 42, so that the baffle plate and barrel turn as a unit, it being understood that the posts 14 pass through apertures 14' in the baffle plate, so that the latter can move the tumbler. To hold the barrel in the casing the bracket 35 may be provided with a lug 43, Figs. 3 and 13, which engages under an internal annular flange 44 on the inner end of the barrel. To permit access to the lock the casing may have a removable plate 45 at its inner end.

From the foregoing description taken in connection with the accompanying drawings, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as fall within the scope of the appended claims. 105

Having thus described my invention, I claim as new and desire to secure by Letters Patent:

1. A lock comprising a stationary casing having a slot, a barrel within the casing and having a slot; a single bolt mounted within the barrel on a fixed pivotal center and having its end normally disposed in the slot and adapted to be engaged by opposite edges of the slot in the barrel for projecting or retracting the bolt by the relative turning of the casing and barrel, means normally preventing the relative turning of the casing and barrel, and a tumbler mechanism for unlocking the barrel from the casing for permitting relative rotation.

2. A permutation lock comprising a casing, a barrel rotatably mounted therein, said casing and barrel having registering slots, a bolt mounted in the barrel and movable through the slots by the relative rotation of the casing and barrel, a baffle element normally held from rotation and operatively connected with the barrel for preventing turning thereof, tumblers controlling 130

the unlocking of the baffle element from the said holding means, and means for moving the baffle element to unlocked position when the tumblers are in a predetermined 5 position, whereby the barrel can turn.

3. A permutation lock comprising a casing, a barrel rotatable therein, a swinging bolt movable out of the barrel and casing in a plane transverse to the axis of rotation 10 of the barrel, and a tumbler-controlled means normally holding the barrel against rotation, the pivotal center on which the bolt swings being eccentric to the axis of the barrel and the barrel having spaced 15 means engageable with the opposite sides of the bolt for swinging the same inwardly or outwardly.

4. A permutation lock comprising a bolt, fixed means on which the bolt is mounted, 20 a rotary element normally stationary and adapted upon rotation to actuate the bolt, a plurality of tumblers, a baffle plate co-operating with the tumblers, a push button for moving the baffle plate when the tumblers are in a predetermined position, whereby the rotatable element is unlocked 25 and can be turned.

5. A permutation lock comprising a casing, a barrel rotatable therein, a bolt adapted to be actuated by the barrel, a plurality of tumblers disposed in the barrel, a baffle plate mounted in the barrel and co-operating 30 with the tumblers, means fixed in the barrel and normally engaged with the baffle plate for preventing rotation of the barrel, and a pushbutton capable of being pressed when the tumblers are in a predetermined 35 position for disengaging the tumbler plate

from the said fixed means and permitting the tumbler to be turned.

6. A permutation locking comprising a 40 casing, a barrel rotatable therein, a bolt adapted to be actuated by the barrel, a plurality of tumblers disposed in the barrel, a baffle plate mounted in the barrel and co-operating with the tumblers, means fixed in the barrel and normally engaged with the baffle plate for preventing rotation of the barrel, a pushbutton capable of being 45 pressed when the tumblers are in a predetermined position for disengaging the tumbler plate from the said fixed means and permitting the tumbler to be turned, and yielding interlocking means between the tumblers and barrel for holding the tumblers 50 yieldingly in adjusted position.

7. The combination of a casing, a barrel 55 rotatable therein, a bolt adapted to be projected from the barrel and casing, a central fixed member, an axially movable baffle plate associated with the said member and normally prevented from turning thereby, means connecting the barrel with the baffle plate to prevent the barrel from turning 60 while the baffle plate is locked, spring means 65 acting on the baffle plate, a pushbutton for moving the baffle plate with respect to the central fixed means to position for permitting the baffle plate to turn with the barrel, and tumblers adjustably mounted in the 70 barrel and co-operating with the baffle plate to permit movement of the latter by the pushbutton only when the tumblers are in a predetermined position.

OSKÁR KLEIN.
